ELEVATOR.

1,150,515.

Specification of Letters Patent.

Patented Aug. 17, 1915.

Application filed April 20, 1915. Serial No. 22,636.

To all whom it may concern:

Be it known that I, FRANK W. GRADY, a subject of the King of England, residing at Taft, in the county of Kern and State of California, have invented a new and useful Elevator, of which the following is a specification.

The present invention appertains to elevators for raising sucker, pump or polish rods, and well tubings or casings, and aims to provide a novel and improved latch device for such an elevator, whereby the elevator may be readily applied to the rod or tubing, and latched to hold its position thereon, and in order that the elevator may be readily manipulated for applying and removing the same, the latch being readily released when it is desired to detach the elevator.

It is also within the scope of the invention to provide a latch device for elevators of the type indicated, which device is comparatively simple, compact, non-encumbering and inexpensive in construction, as well as being safe, time-saving, convenient, serviceable, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a plan view of one form of sucker or polish rod elevator, parts being broken away to illustrate the latch device. Fig. 2 is a side elevation of the said elevator. Fig. 3 is a sectional view taken on the line 3-3 of Fig. 2. Fig. 4 is a view similar to Fig. 1 of a second form of elevator with a modified form of latch device. Fig. 5 is a plan view of a well tubing or casing elevator, portions being broken away to illustrate the latch device. Fig. 6 is a sectional view taken on the line 6-6 of Fig. 5. Fig. 7

is a side elevation of the elevator illustrated in Fig. 5.

Referring specifically to Figs. 1, 2 and 3, the elevator comprises a circular body or casting 1 having trunnions 2 projecting from diametrically opposite points of its periphery to be journaled within the terminal eyes 3 of an ordinary bail 4, as is well understood in the art. The body 1 is provided with a radial slot 5 for receiving the sucker or polish rod 6, the upper end of the rod 6 being provided with a head or member 7 to seat upon the body 1 whereby the elevator can carry the rod 6 properly when the elevator is applied thereto.

The body 1 is provided with a latch device, and to this end the body is provided diametrically opposite the slot 5 with a recess 8 in its periphery, and the body is further provided with an arcuate bore or passage 9 extending from one end of the recess to one side of the slot 5 between the ends of the slot or adjacent the inner end thereof. An arcuate latch bolt 10 of circular cross section is slidable within that end portion of the bore 9 remote from the recess 8, and a block or member 11 is fitted snugly within the recess 8 to fill the same, the block or member 11 being secured within the recess 8 by means of screws or other securing elements 12 engaged through the block and taking into the body 1. The block 11 closes its respective end of the bore 9, and a coiled wire expansion spring 13 is disposed within the bore 9 between the latch bolt 10 and the block 11 to yieldably project the latch bolt into the slot 5. The projecting end of the latch bolt 10 is beveled, as at 14, whereby when the elevator is applied to the rod 6, the rod in being received by the slot 5 will force the latch bolt backwardly against the tension of the spring 13, so that when the rod reaches the inner end of the slot 5, the latch bolt 10 will snap over the side of the rod for holding the elevator in place upon the rod.

The periphery of the body 1 is provided with a channel 15 extending from that side of the slot 5 from which the bore 9 extends, and a slot 16 is provided between the channel 15 and bore 9 adjacent the said side of

the slot 5. A stem 17 has its inner end threaded or otherwise engaged to the latch bolt 10 and works within the slot 16, and the outer or free end of the stem 17 is provided with a curved finger piece 18 working within the channel 15. The finger piece 18 is thus housed within the channel, and is not liable to be accidentally swung by the engagement of an object with the elevator.

10 The parts may be readily assembled, and when the block 11 is removed from the recess 8, the latch bolt 10 and spring 13 may be introduced in succession into the bore 9 from the recess 8, it being understood that 15 the stem 17 is detached from the latch bolt. Then, the block may be secured within the recess 8 to hold the spring and latch bolt within the bore 9, and the stem 17 may then be inserted through the slot 16 and properly 20 engaged to the latch bolt. The stem 17 in working within the slot 16 of limited length will limit the reciprocatory movement of the latch bolt properly and will also prevent the latch bolt from turning which would be 25 liable to cause it to bind within the bore 9, and which would be objectionable for other reasons.

The body 1 may be readily applied to the 30 rod 6 by passing the body 1 astride of the rod, the rod being received by the slot 5 and being moved past the latch which will cause the latch to snap over the side of the rod for holding the body and rod assembled. The present latch device is not liable to accidentally release itself, and has the desirable 35 attributes which are essential in a device of the present character. The latch bolt may be readily released by pressing the finger piece 18 backwardly or away from the slot 40 5. The latch device does not encumber the elevator body, but at the same time serves its office in a thoroughly efficient and desirable manner.

In Fig. 4, the modified form of elevator is 45 provided with a modified form of latch device, which embodies the features of the latch device above described. The body 1' is provided with the diametrically opposite trunnions 2' for engaging the terminal eyes 3' of the bail 4', and the body 1' is also provided with the radial slot 5' for receiving the rod 6'. The body 1' is provided with a straight bore 9' leading to one side of the slot 5', and the latch bolt 10' is also 55 straight and slides snugly within the inner end portion of the bore 9' to project into the slot 5'. A plug 11' is threaded or otherwise engaged into the outer end of the bore 9' and a coiled wire expansion spring 13' is disposed within the bore 9' between the plug 11' and latch bolt 10' to yieldably project the latch bolt inwardly. The inner end of the latch bolt is beveled, as at 14', whereby the latch bolt will operate in the manner of 60 65 the latch bolt 10 above described. The ad-

jacent ends of the latch bolt 10' and plug 11' are preferably provided with sockets 19 for receiving the ends of the spring 13'. The body 1' is provided with a channel 15' extending from the slot 5', and is further provided with a slot 16' between the channel 15' and bore 9', which slot 16' receives the stem 17' which is engaged to the latch bolt 10'. The stem 17' has a curved finger piece 18' working within the channel 15'. 70 75

The modified form of latch operates practically in the same manner as the first form, and a reiteration of the operation is therefore not thought necessary, it also being noted that the parts of the modified form of latch device may be assembled practically in the same manner as with the first form. 80

The elevator illustrated in Figs. 5, 6 and 7 is adapted for raising a well tubing or casing, and is of especial construction for that reason. The well tubing or casing elevator comprises a body embodying two arcuate sections 1^a and 1^b hinged together at 1^c. The section 1^a is provided with an arcuate slot 1^d extending from the hinge 1^c, 90 and the adjacent end of the section 1^b is provided with an extension 1^e arranged to swing into the slot 1^d when the sections are swung together. The free end of the section 1^a is provided with a lug or portion 1^f projecting tangentially therefrom, and the free portion of the section 1^b is bifurcated or forked to provide the portions 1^g arranged to straddle the lug 1^f when the sections are swung together. The lug or portion 1^f is of sufficient length to project beyond the portions 1^g when the sections are swung together, the portions 1^g being arranged to swing against the free end of the section 1^a at the opposite sides of the lug 1^f. 100 105

The section 1^a is provided adjacent its ends or adjacent the hinge 1^c and lug 1^f with outstanding apertured ears 2^a for the engagement of the terminal eyes 3^a of the bail 4^a whereby the elevator may be properly carried by the bail, it being noted that one section of the body is attached to the bail, while the other section is adapted to swing freely in applying and removing the elevator. 110 115

The lug 1^f carries the latch device which is similar to the latch devices above described.

The lug 1^f is provided with a bore 9^a extending therethrough, and a latch bolt 10^a is slidably within the inner end portion of the bore 9^a, while a plug 11^a is threaded or otherwise engaged into the outer end of the bore. A coiled wire expansion spring 13^a is disposed within the bore 9^a between the latch bolt and plug, for yieldably projecting the latch bolt inwardly. The inner end of the latch bolt is beveled, as at 14^a, whereby when the free end of the section 1^b is 120 125 130 swung toward and against the free end of the latch bolt 10^a the latch bolt 10^a will be urged into the bore 9^a and the plug 11^a will be urged into the outer end of the bore 9^a to hold the latch bolt 10^a in its engaged position.

the section 1^a, the latch bolt will be pressed into the bore 9^a to allow the free end of the section 1^b to pass the latch bolt, and whereby the latch bolt will then be projected or 5 snapped into engagement with a keeper notch 14^b provided in the section 1^b between the portions 1^c.

The free end of the lug 1^f is provided with a channel 15^a parallel with the bore 10 9^a, and the lug has a slot 16^a between the channel 15^a and bore 9^a. A stem 17^a works within the slot 16^a and is secured to the latch bolt, and the stem is provided with a curved finger piece 18^a working within the 15 channel 15^a.

In applying the elevator to a well tubing or casing, the latch 10^a is released by pressing the finger piece 18^a outwardly, and the section 1^b is then swung open so that the 20 well tubing or casing may be moved between the two sections. When the section 1^b is swung open, the extension 1^d thereof will project between the ends of the section 1^a, and then when the tubing or casing is 25 received between the two sections, it will engage the extension 1^d and then by moving the section 1^a against the tubing, the section 1^b will at the same time be swung to closed position against the free end of the 30 section 1^a, and the latch device will automatically engage the section 1^b for holding the two sections together. In this manner, the elevator may be applied to the well tubing or casing by one hand, since when the 35 section 1^b is swung open, the section 1^a may be manipulated by the hand for conveniently applying the elevator to the tubing or casing. The sections or jaws 1^a and 1^b are thus automatically closed and latched when 40 they are applied to the tubing or casing, and the latch device has the advantages of the latch devices above described.

Having thus described the invention, what is claimed as new is:

1. In an elevator of the character described, a body having a bore, a channel, and a slot between the channel and bore, a latch bolt slideable within one end portion of the bore, a member engaged to the body to close the other end of the bore, an expansion spring within the bore between the said member and latch bolt, a stem engaged to the latch bolt and working within the said slot, the stem having a finger piece working within the said channel. 45

2. In an elevator of the character described, a pair of arcuate sections hinged together, the free end of one section having a portion projecting therefrom, the free end of the other section being bifurcated and having portions adapted to straddle the first mentioned portion and seat against the free end of the first mentioned section, the first mentioned portion having a bore extending therethrough, a channel at its free end, and 60 a slot between the channel and bore, a latch bolt slideable within one end of the bore, a member engaged into the other end of the bore, an expansion spring within the bore between the said member and latch bolt, the 65 second mentioned section having a keeper between said portions for receiving the latch bolt, a stem engaged to the latch bolt and working in said slot, and the stem having a finger piece housed within the channel. 70

In testimony that I claim the foregoing as my own, I have hereto affixed my signature in the presence of two witnesses.

FRANK W. GRADY.
